ELECTRIC FURNACE WITH COOLING MEANS

Application filed April 7, 1931. Serial No. 528,323.

My present invention relates to improvements in the mechanical construction of electric furnace shells and electric furnace refractory supporting structures, particularly 5 the door and roof structures.

In electric arc furnaces built with cylindrical shells, and with door ways to the chamber within, the arch brick forming the top of the door way is subject to extreme heat from 10 the arcs and to wear and to the effect of heating and cooling so that it is one part of the lining which wears out more quickly than others. One object of my present invention is an improved arch cooler construction to in- 15 crease the life of this part of the refractory lining.

Electric arc furnaces are usually provided with removable roofs which either rest on the top of the shell and brick wall, or rest 20 on the top of the wall inside the shell. These roof rings are usually made by bending a steel channel section with the flanges in so as to form a support for the brick arch structure, or else the rings are made up of angles 25 and plates forming a similar ring structure. In certain cases water cooling pipes have been mounted inside this ring structure. One object of my invention is an improved ring structure comprising an outer ring plate with 30 a pipe welded to it at the bottom on the inside forming a combined cooler and arch support.

These and other details of my invention will be better understood by reference to the 35 annexed drawings, in which Fig. 1 is a plan view of a furnace embodying my invention, showing the roof cut away in part. Fig. 2 is a sectional elevation of the furnace of Fig. 1 through the center line A A. Fig. 3 is an 40 elevation view partly in section of one embodiment of my invention, the section being taken about along a line corresponding to the line B B of Fig. 1 to cut away the front flange of the channel forming the bottom of 45 the cooling cavity above the arch.

Referring to these figures, the furnace shell consists of a bottom head 1 to which is welded a cylindrical plate 2 forming the shell proper, and to which in turn is welded a reinforcing 50 channel 3 at the top of the shell plate 2. The

shell is lined with a hearth 4 and walls 5, extending up to the line 6. A door way 7 into the furnace chamber is formed by arch brick 8 above the door way resting on side brick 9. The door way is closed by a refractory lined 55 door 10 which fits against a plate 11 which in turn fits against the structural members 12 at the bottom and 13 at the top welded to the shell. The top member in these illustrations is a channel section. It has a web 14 and inner flange 15 and outer flange 16. The front view of the door structure in Fig. 3 shows the curved surface of this channel at 14 just above the arch brick. The weld at the top of the inner flange is indicated at 17 and a cover 60 plate 18 may be seen in Figs. 2 and 3. The channel is welded to the shell plate 2 and the inner flange of this channel is welded to plate 2 at 19 and 20. The water cavity is formed by welding the top plate 18 to the top of the 70 channel flange 15 and to the inside of the shell plate 2. An opening is provided at the lower part of the cooling cavity thus formed at both sides of the cavity as indicated by the 75 pipes 21 and 22 which serve for circulation of cooling water.

This forms a very simple and substantial and efficient construction. The channel reinforces the shell at the door way. It also forms the cooling cavity with the necessity of only 80 a single piece of plate, like that at 18 in addition to the channel and shell plate. The flat inner surface of the channel forms a surface for a second arch 23 to abut over the door way 85 arch brick 8 and provides for protection of the shell in case the arch brick of the door way is allowed to become worn away.

It is understood that my construction is not limited to the use of the channel member or to the shape of cooling cavity indicated but that I may build this structure up in other ways and accomplish the purpose of my invention without getting away from the essentials thereof.

The construction of the roof structure will 95 now be described. I have shown the roof ring of my present invention made of a steel plate 24 formed with slightly less outside diameter than the inside diameter of the shell plate 2. This plate 24 forms a complete ring and the 100

ends are welded together at some convenient place. Inside this ring 24 and at the bottom of it an iron pipe is welded to it so as to be approximately flush on the bottom with the bottom of the plate 24. The welding need not be completely around the ring but is preferably above the pipe as well as on the lower part as indicated at 25 and 26. This pipe forms a complete circle inside the plate except between the two outlets 27 and 28 which are brought up and preferably threaded for connection of cooling water hose fittings. The roof ring is shown with lift hooks at 29 and 30. Inside the ring the roof arch brick are shown. These extend across the furnace chamber. They are supported by means of the pipe and by refractory material indicated at 31 forming a skew back. This may be brick or it may be rammed-in refractory material. The roof ring and refractory held in it rest inside the furnace shell on the top of the refractory chamber wall.

My improved roof ring not only is simpler to construct but also avoids the burning away of the ring structure as when the ring has an inwardly extending flange instead of the pipe. Furthermore, in case of wear of the wall brick till they become excessively thin, even if the pipe is exposed directly to the heat within, the water cooling protects it and prevents damage.

What I claim is:

1. In an electric furnace having a plate metal shell with a curved surface through which is a door way into a refractory lined chamber within, a cooler for the brick work above the door way, said cooler comprising a weld-sealed water cavity between the shell plate and the refractory material inside the shell above the door way, and inlet and outlet openings for water cooling this cavity.

2. In an electric furnace having a cylindrical plate shell, a door way arch cooler comprising a water cavity between the inside of the curved shell plate and another plate member forming with the curved plate a sector of a circle and having top and bottom plates all welded together to be water tight and having openings for water circulation through the cavity thus formed.

3. In a cylindrical electric furnace shell having a door opening, a refractory lining within and a door way through said lining to the chamber within, an arch above said door way, and a cooler for the top of said arch comprising a curved plate member conforming to the top of said arch, an inner plate member forming a sector shaped opening between it and the shell above the arch plate, and a top member for the water cavity thus formed, said member being welded together and having water circulation means.

4. In an electric furnace shell, having a refractory lining and door way therein, surrounded by a brick arch, a door arch cooler

formed by a bent channel member arched over the top of the brick arch and having a flange joining with the inside of the shell plate above the arch and welded thereto, water circulating means opening into the cavity formed by said channel, and a top plate welded to the inside of the shell and to the top of said flange.

5. In an electric arc furnace a roof ring for supporting a brick arch, said ring comprising a circular plate of steel and a pipe welded to said plate inside it at the bottom for supporting the brick arch and for cooling the furnace structure.

In testimony whereof I affix my signature. 80
